UNITED STATES PATENT OFFICE

RUDOLF URBAN, OF PODBREZOVÁ, CZECHOSLOVAKIA

APPARATUS FOR ROLLING SEAMLESS PIPES

Application filed March 13, 1928, Serial No. 261,313, and in Czechoslovakia March 15, 1927.

The present invention relates to an apparatus for the rolling of seamless or weldless pipes or tubes, and consists in means, whereby the work is transferred for the purpose of treatment from one pair of rolls to the next following second, third, etc., by means of the mandrel on which the work has been placed by the treatment in one pair of rolls. In this way it becomes possible to do the whole of the rolling with one heating of the work. It is at the same time immaterial whether ingots of solid cross section, or ingots already holed are being treated.

By means of the apparatus of the present invention, seamless tubes of maximum or minimum diameter can be manufactured.

A construction of apparatus embodying the invention is illustrated by way of example in the accompanying drawings, in which—

20 Figure 1 is a side elevation, partly in section, of an apparatus embodying the invention.

Figure 2 is a similar view showing the parts in a different position.

25 Figure 3 is a detail section, on an enlarged scale of the mandrel and a billet thereon.

Figure 4 is a plan.

Figure 5 is a plan of portion of the apparatus, taken beneath the base plate for the 30 mandrel supporting slide.

In the construction illustrated, the block or billet 1, which has been raised to a bright red heat is perforated by action of the first pair of rolls I, forcing it over the hollow mandrel 2, against the removable point 3.

35 The mandrel 2 is mounted in an adjustable bracket 4 by means of a double T-piece 5, and encloses a pipe by which water, admitted into the bored cross-pin of the piece 5, is guided to the end of the mandrel from which it escapes through suitable openings.

40 The end of the cross-pin 5 opposite that at which water enters, and which projects out of the bracket 4, carries a gear wheel 8 which can mesh with a fixed rack 9.

45 When, therefore, the bracket 4 is moved from adjacent the pair of rolls I toward the pair of rolls II (or from the position shown in full lines in Figure 1 to the position indicated by dotted lines) the point 3 will be re-

moved from the mandrel 2 and the latter moved in a horizontal direction out of the range of the pair of rolls I.

By engagement of the gear wheel 8 with the rack 9, during movement of the bracket 4 to the right in Figure 1 from the full line position, the mandrel will be turned through an angle of 180° and with its end positioned within the working range of the second pair of rolls II in which the work is subjected to 50 further treatment.

If a third and succeeding working operation is to be carried out, another mandrel receives the work from the pair of rolls II and brings it, in the manner just described, into position to be operated upon by a third pair of rolls, and from the latter to other following pairs of rolls, if necessary.

55 If, however, the rolling of the pipe or tube is finished in the pair of rolls II, it is moved by the cooperating mandrel 10 of such rolls and conveying means 11 into a calibrating and straightening machine (not shown). The head 3 for initially forming a bore in the billet is not replaced on the mandrel when the tube is acted upon by the pair of rolls II or subsequent pairs of such rolls. As shown in Figure 3, the diameter of the free end of the mandrel 2 is substantially that of the mandrel 10 and the action of the rolls II is to draw 60 the tubular billet from the mandrel 2 onto the mandrel 10.

65 The movement of the bracket 4 from operative relation to the pair of rolls I into similar relation to the pair of rolls II and back again, is effected by shaft 12 which is connected by suitable gearing with the shafts of the rolls I.

The shaft 12 carries two cams 14, 15, which act on the ends of rotatably mounted double levers 16, 17, the other ends of which are united by connecting rods 18, 19, with double levers 20, 21.

70 The upper ends of the double levers are connected to the bracket 4, so that by the action of the cam 14, the bracket will be moved toward the pair of rolls II and by the action of the cam 15 toward the pair of rolls I.

75 In order to bring about an automatic movement of the work on the mandrel for the pur-

pose of bringing it into position to be acted on by the pair of rolls II, there is mounted on the bracket 4 a double arm lever 22, one end of which extends into position to strike a stop 23 as the mandrel supporting bracket 4 is shifted from the full line to the dotted line position (Figure 1).

5 The upper end of the lever 22 is thereby moved toward the pair of rolls II and moves the work longitudinally of the mandrel away 10 from a sleeve 24, which work is held in a fork at the end of the lever, and advances the work.

In the illustrated embodiment of the invention 15 the train of gearing before referred to for connecting the shafts of the first pair of rolls with the shaft 12 includes a pinion 35 geared to the rolls and meshing with a gear 36 on the shaft 12.

20 The work 1 is introduced into the first pair of rolls I by means of a lever 29, the movement of which is dependent on that of the lever 21 (being connected to said lever by a rod 30) in such a manner that the mandrel 25 is introduced at one side, whilst the work is simultaneously introduced at the other side into operative relation to the members of the first pair of rolls I.

What is claimed is:—

30 1. In an apparatus for rolling seamless, weldless, pipes or tubes, the combination of a pair of rolls, a reciprocable mandrel support, a mandrel mounted on said support to swing about a horizontal axis adjacent one 35 end and adapted to be positioned to receive a perforated billet from the pass between said rolls, a pinion connected with the mandrel and in co-axial relation to the said horizontal axis thereof, a relatively stationary rack 40 adapted to cooperate with said pinion to oscillate the mandrel as its support is reciprocated, means for reciprocating the mandrel support, and means actuated by movement of the mandrel support after the mandrel has 45 been turned through an angle of approximately 180° for stripping the perforated billet from the mandrel.

2. In an apparatus for rolling seamless, weldless, pipes or tubes, the combination of 50 a pair of rolls, a reciprocable mandrel support, a mandrel mounted on said support to swing above a horizontal axis adjacent one end and adapted to be positioned to receive a perforated billet from the pass between 55 said rolls, a pinion connected with the mandrel and in co-axial relation to said horizontal axis thereof, a relatively stationary rack adapted to cooperate with said pinion to oscillate the mandrel as its support is 60 reciprocated, means for reciprocating the mandrel support, and means actuated by movement of the mandrel support after the mandrel has been turned through an angle of approximately 180°, and the pinion has 65 moved out of engagement with the rack, for

stripping the perforated billet from the mandrel.

3. In an apparatus for rolling seamless, weldless, pipes or tubes, the combination of 70 two pairs of rolls arranged with their passes in substantial alignment, a mandrel support arranged between the pairs of rolls and adapted to be bodily reciprocated in a direction substantially at right angles to the axes of said rolls, a mandrel mounted to turn bodily about a substantially horizontal axis on said support and to be positioned to cooperate with one of the pairs of rolls to receive a perforated billet therefrom or to present such 75 perforated billet in alignment with the pass between the other pair of rolls, a relatively stationary rack, a pinion connected with the mandrel in co-axial relation to said horizontal axis thereof, and adapted to engage the rack as the mandrel support is reciprocated to turn the mandrel through an angle of approximately 180° and from operative relation to the first pair of rolls to operative relation to the second pair of rolls, and means 80 for reciprocating the mandrel support. 85

4. In an apparatus for rolling seamless, weldless, pipes or tubes, the combination of 90 two pairs of rolls arranged with their passes in substantial alignment, a mandrel support arranged between the pairs of rolls and adapted to be bodily reciprocated in a direction substantially at right angles to the axes of said rolls, a mandrel mounted to turn bodily about a substantially horizontal axis on said support and to be positioned to cooperate with one of the pairs of rolls to receive a perforated billet therefrom or to present such 95 perforated billet in alignment with the pass between the other pair of rolls, a relatively stationary rack, a pinion connected with the mandrel in co-axial relation to said horizontal axis thereof and adapted to engage the rack as the mandrel support is reciprocated to turn the mandrel through an angle of approximately 180° and from operative relation to the first pair of rolls to operative relation to the second pair of rolls, means 100 for reciprocating the mandrel support. 105

5. In an apparatus for rolling seamless, weldless, pipes or tubes, the combination of 110 a pair of rolls, a reciprocable mandrel support, a mandrel mounted on said support to swing about a horizontal axis, and adapted to be positioned to receive a perforated billet from the pass between the members of the second pair of rolls, a pinion connected with the mandrel and in co-axial relation to said horizontal axis thereof, a relatively stationary rack adapted to cooperate 115 with the mandrel in co-axial relation to said horizontal axis and adapted to engage the mandrel as the mandrel support is reciprocated to turn the mandrel through an angle of approximately 180° and from operative relation to the first pair of rolls to operative relation to the second pair of rolls, means for reciprocating the mandrel support, a second mandrel extending into the pass between the members of the second pair of rolls, and means actuated by movement of the mandrel support, after the pinion has passed from engagement with said rack, for moving the perforated billet from the first said mandrel on to the other mandrel. 120

6. In an apparatus for rolling seamless, weldless, pipes or tubes, the combination of 125 a pair of rolls, a reciprocable mandrel support, a mandrel mounted on said support to swing about a horizontal axis, and adapted to be positioned to receive a perforated billet from the pass between the members of the second pair of rolls, a pinion connected with the mandrel and in co-axial relation to said horizontal axis thereof, a relatively stationary rack adapted to cooperate 130 with the mandrel in co-axial relation to said horizontal axis and adapted to engage the mandrel as the mandrel support is reciprocated to turn the mandrel through an angle of approximately 180° and from operative relation to the first pair of rolls to operative relation to the second pair of rolls, means for reciprocating the mandrel support, a second mandrel extending into the pass between the members of the second pair of rolls, and means actuated by movement of the mandrel support, after the pinion has passed from engagement with said rack, for moving the perforated billet from the first said mandrel on to the other mandrel.

- ate with said pinion to oscillate the mandrel as its support is reciprocated, means actuated by the driving shaft of the rolls for reciprocating the mandrel support, and means actuated by movement of the mandrel support after the mandrel has been turned through an angle of approximately 180° for stripping the perforated billet from the mandrel.
6. In an apparatus for rolling seamless, weldless, pipes or tubes, the combination of a pair of rolls, a reciprocable mandrel support, a mandrel mounted on said support to swing about a horizontal axis, and adapted to be positioned to receive a perforated billet from the pass between said rolls, a pinion connected with the mandrel and in co-axial relation to said horizontal axis thereof, a relatively stationary rack adapted to cooperate with said pinion to oscillate the mandrel as its support is reciprocated, means actuated by the driving shaft of the rolls for reciprocating the mandrel support, including two levers fulcrumed intermediate their ends and connected to the mandrel support, a second pair of levers connected by links to the first said pair, a pair of rotatable cams for rocking said levers to reciprocate the mandrel support, and means for automatically stripping the perforated billet from the mandrel after it has been turned through an angle of approximately 180°.
7. In an apparatus for rolling seamless, weldless, pipes or tubes, the combination of a pair of rolls, a reciprocable mandrel support, a mandrel mounted on said support to swing about a horizontal axis, a pinion connected to the mandrel and in co-axial relation to said horizontal axis thereof, a relatively stationary rack adapted to cooperate with said pinion to oscillate the mandrel as its support is reciprocated, means for reciprocating the mandrel support, a fork pivotally mounted on the mandrel support and adapted to have the mandrel extend between its members when it has been turned through an angle of approximately 180°, and means for rocking said fork to strip the perforated billet from the mandrel body by movement of the mandrel support after the pinion has passed from engagement with the rack.

RUDOLF URBAN.
